UNITED STATES PATENT OFFICE

CLARENCE C. SHIPP, OF INDIANAPOLIS, INDIANA

MIDDLE-SECTION HEATER FOR RADIATORS

Application filed September 25, 1929. Serial No. 395,011.

In the heating and ventilating of school-
rooms, halls, churches, and the like, with
steam radiators, coils in sufficient number
are used to give radiation which will be ample
5 to heat the room to 72° F. in the coldest
weather; and, for proper ventilation, outside
air is introduced into the room through a box
surrounding all but one or two sections locat-
ed at each end of the radiator. Brought thus
10 into intimate contact with the major number
of radiator sections, the cool air from out-
doors is heated before it is discharged into
the room.

Difficulty is experienced in moderately cold
15 weather in regulating the temperature in
rooms equipped as above described, because,
by only partially opening the valve in the
steam supply pipe to reduce the radiation,
the radiator sections nearest to the valve are
20 heated, and those are the sections which are
not enclosed by the box supplying cold air
from outside of the building, but are the sec-
tions which are left unenclosed, purposely, to
heat the walls and glass of the room. The
25 result is, that outside air, entirely unwarmed,
and perhaps damp and disagreeable, con-
tinues to be discharged into the room through
the ventilator box.

The object of this invention is to provide
30 means for discharging the heat to the middle
sections of a radiator, instead of into the sec-
tion nearest the supply valve, as heretofore,
in order that the cold air coming through the
wall and radiator boxes from the outside, will
35 be warmed whenever any steam at all is in-
troduced into the radiator.

I accomplish the above, and other minor
objects which will hereinafter appear, by the
40 mechanism illustrated in the accompanying
drawing, in which—

Fig. 1, is a front elevation and partial vertical
section of a radiator, equipped with a
ventilator box, and also equipped with my in-
vention; and

45 Fig. 2, is a vertical section of same on the
line 2—2 of Fig. 1.

The radiator here shown has twelve sec-
tions 2, of which, the eight middle ones are
50 surrounded by a sheet-metal radiator box 3,
leaving two sections outside of the box at each

end. The radiator may have more, or less,
than twelve sections, depending upon the
service required of it, and the number of sec-
tions at the end, remaining outside of the box,
may also vary. Sections on the outside of the 55
box are so exposed for the purpose of cir-
culating and heating the air of the room in
order to warm the walls and window glass,
while those contained within the box 3 are
to warm a supply of air entering the box from 60
the outside of the house through a wall box
4, which box 4 discharges into the base 5
of the radiator box 3. The box base 5 is here
shown as having a downwardly swinging
door 6, which is automatically closed, nor- 65
mally, by a spring 7, but this door construc-
tion forms no essential part of this invention
and may be omitted if desired. The wall box
4 is provided with a damper 8, which is con-
nected by a chain 9, with a thermostat 10, for 70
the purpose of automatically regulating the
supply of outside air which enters through
the wall box.

Steam is admitted to an end section of the
radiator, through a supply pipe 11, the area 75
of the opening through which is controlled
by a hand-operated valve 12. Ordinarily the
steam, entering the first section of a radiator,
passes successively through all of the sections
and discharges through a return pipe 13, 80
which is controlled by a trap 14, all of well
known and usual construction.

With such an installation as I have thus
far described, when it is desired in compara-
tively mild weather, to furnish less than the 85
maximum heat through the radiator, the
hand valve 12 is only partly opened and the
nearest radiator section or perhaps the two
first sections are heated, but the rest of the
sections remain cold, and the outside air com- 90
ing in through the box 4 retains whatever
disagreeable atmospheric conditions are ex-
isting out of doors.

To remedy this, I provide a pipe 15, hav-
ing an open end which is threaded on the 95
outside, and having its opposite end closed.
The threaded end of the pipe is screwed into
the bushing 16, with which the steam supply
pipe also connects, as shown in Fig. 1, and
the pipe is passed through the nipples 17, by 100

which the several sections of the radiator are joined.

In the form here shown they have inside ribs 18, primarily to engage a wrench for screwing them into place, and these ribs 5 serve to center my pipe 15, and prevent vibration of the pipe such as otherwise might have a tendency to injure the threads where the threaded end of the pipe is made fast.

10 The pipe 15 is preferably of the right length to reach and extend through the middle section of the radiator and it has a series of holes 19, formed through its walls, at top and sides, for the discharge of steam, 15 and bottom holes 20 for the discharge of any water that may accumulate. The total area of the top and side holes should be at least equal to the cross sectional area of the pipe itself, and they should be opposite the hollow interior of the sections for maximum freedom of discharge.

By the above construction, steam delivered to the radiator is discharged into the middle sections where it will influence the temperature and humidity of the air coming in from 25 out of doors and heat the room until the maximum capacity of these coils is reached. After that the unenclosed end coils heat up and furnish the additional radiation, but the 30 outside air is always tempered before it is discharged into the room.

Having thus fully described my invention, what I claim as new and wish to secure by Letters Patent, is—

35 1. A radiator having a plurality of intermediate sections and other sections toward each end from the intermediate ones, nipples uniting the sections, a pipe supplying steam at one of the end sections, a valve in the pipe, 40 and a pipe extension from the end of the first pipe passing through some of the nipples and discharging into sections remote from the outside section and spacing members centering the pipe in the nipples.

45 2. In combination with a radiator, a housing about a portion of the radiator open at one end, a fresh air duct discharging into the housing, and steam supply means discharging initially into said housed radiator portion.

50 3. In combination with a radiator, a housing about a portion of the radiator open at one end, a fresh air duct discharging into the housing, and steam supply means discharging initially into said housed radiator portion, the unhoused portion of the radiator being connected to the housed portion to receive the flow of steam from said means after flowing through the housed portion.

60 In testimony whereof I affix my signature.
CLARENCE C. SHIPP.
